SPRING MOUNTED ROCKING HORSE

Adrain Dodson, Columbus, Miss.

Application September 12, 1952, Serial No. 309,269

10 Claims. (Cl. 272—53.1)

My invention relates broadly to amusement devices and more particularly to devices for simulating the appearance and movement of bucking broncos, Brahma bulls, horses, etc.

One of the objects of my invention is to provide a construction of figure simulating an animal which is floatingly supported on coil springs which may be rendered selectively effective by displacement of the effective mass of the rider for reproducing in similitude the bucking and prancing of the animal.

Another object of my invention is to provide a construction of figure mounted with respect to a set of rockers in a position in which the figure is normally supported in a state of balanced equilibrium on centrally arranged coil springs and is subject to the alternate effect of compression and expansion of front and rear coil springs operating to impart forces to the figure simulating bucking and prancing movements.

Still another object of my invention is to provide a multiple arrangement of springs for mounting a figure on a rockable support, including an arrangement of pedals which may be pressed by the rider for rendering the springs selectively effective for producing an effect of bucking and prancing of the figure.

Still another object of my invention is to provide a structure of rocking figure having central coil spring supports and front and rear coil springs, including operating devices pivotally mounted with respect to the rocking support for the figure and selectively effective through pedal control means operated by the rider for producing motions of the figure simulating bucking and prancing movements.

Other and further objects of my invention reside in the distribution of coil springs within a figure which may be alternately subjected to expansion and compression forces for imparting movement to the figure simulating bucking and prancing as set forth more fully in the specification hereafter following by reference to the accompanying drawings, in which:

Figure 1 is a perspective view of a hobby horse embodying my invention, the view being partially broken away and illustrated in section for showing the arrangement of the spring mounting of the figure by which bucking and prancing movements of the figure are reproduced in similitude; Fig. 2 is a vertical sectional view taken substantially on line 2—2 of Fig. 1 and illustrating the arrangement of coil springs for floatatingly mounting the figure in normally balanced equilibrium, certain of the parts being shown in elevation; Fig. 3 is a fragmentary sectional view taken on line 3—3 of Fig. 1 and illustrating one of the angularly disposed suspension springs which serve to mount the front and rear of the figure; Fig. 4 is a horizontal sectional view taken on line 4—4 of Fig. 3; Fig. 5 is a fragmentary view taken through either the front or rear suspension spring and illustrating the condition in which the suspension spring is expanded from a normally balanced condition; Fig. 6 is a view similar to the view shown in Fig. 5 but showing the suspension spring com-

pressed from a normally balanced condition; Fig. 7 is a horizontal sectional view taken on line 7—7 of Fig. 2; Fig. 8 is a fragmentary perspective view showing the arrangement of the pedals for maneuvering the figure into positions representing bucking and prancing of the figure in similitude; Figs. 9, 10, 11, 12, 13 and 14 illustrate progressive conditions of movement of the figure under control of the several coil springs as the rider maneuvers the pedals for the shifting of the effective mass with respect to opposite ends of the figure during the rocking thereof.

My invention is directed to a construction of figure mounted on rockers and supported on four symmetrically arranged coil springs which are rendered selectively effective by the shifting of mass of the rider under control of pedals by which the springs become alternately effective for the delivery of kinetic energy subsequent to the storing up of potential energy in the springs for simulating a bucking or prancing movement of the figure. For purposes of explaining my invention, I have illustrated the invention applied to a hobby horse, but it will be understood that any type of figure may be provided, such as a Brahma bull or representation of any other animal mounted on the functional frame of the device. In one embodiment of my invention, the measurements are approximately two and one-half feet high and four feet long. The overall width of the rockers in such embodiment of my invention is approximately eighteen inches in order to keep the figure from tilting sidewise. The rockers are provided with resilient bumpers at opposite ends thereof which form limiting abutments with the floor and keep the figure from sliding. The rockers provide pivotal connections for front and rear rods and for a pair of centrally arranged rods. The centrally arranged rods extend in a vertical direction, while the front and rear rods are angularly inclined and directed toward the central plane in which the vertically extending rods extend. The figure is provided with a pair of spaced sockets into which the vertically extending rods project. The sockets are floatatingly mounted on the vertically extending rods by means of coil springs normally biased to a position in which the mass of the rider on the figure is resiliently pushing. The front and rear rods are connected with the figure through coil springs normally biased to an intermediate position and capable of displacement through either of two limits, one of which is a compressed position and the other of which is a fully expanded position. The front and rear rods and their associated springs normally maintain the figure in a condition of balanced equilibrium with the mass of the rider on the figure. Under these conditions, the mass of the rider is equally divided between the four springs, the centrally disposed springs being compressed and the front and rear springs being expanded. A set of control pedals are pivotally mounted with respect to both the figure and the vertically extending rods and are maneuvered by the rider in shifting the weight of the rider to differentially condition the springs so that the front and rear springs alternately expand and contract, imparting movement to the figure simulating bucking and prancing.

Referring to the drawings in detail, reference character 1 designates the figure which may be formed from plastic, plywood or metal in a shell having a hollow interior and an outward appearance which simulates the horse, Brahma bull or other animal. The figure has a hollow interior with an open lower portion through which the supports for the figure extend. The figure is mounted upon a pair of rockers represented at 2 and 3, terminating in substantially semi-circular portions 2a and 2b and 3a and 3b at opposite ends thereof having resilient bumpers 2a', 2b', 3a' and 3b' on the lower edges thereof and providing abutment stops for limiting the movement of the rock-

ers. The rockers have centrally disposed pivot connections at their extreme lower positions with a pair of vertically extending standards 4 and 5 which are pivoted to the rockers 2 and 3 at 4a and 5a, respectively. The standards 4 and 5 are fixed in spaced relation with respect to each other in a substantially rigid frame by means of tie standards 4' and 5', whereby the standards 4 and 5 are free to shift in unison on either side of a central plane extending through the figure 1. The standards 4 and 5 are each provided with offset shoulders 4b and 4c; and 5b and 5c, respectively. The upward extensions of the standards 4 and 5 are shown at 4d and 5d which extend coplanar with respect to each other but offset from the vertical axes of the lower portions of the standards at 4 and 5. The upwardly projecting ends of the standards at 4d and 5d extend into tapered sockets represented at 6 and 7. The sockets include closed end members 6a and 7a. The tapered sockets 6 and 7 are fastened together at their closed ends by means of transverse bar 8 which provides securing means for the tapered sockets through angle members 6b and 7b and securing rivets 6c and 7c which pass through the closed end members 6a and 7a and the end walls of the sockets 6 and 7 and are secured through the angle members 6b and 7b which are in turn fastened to bar 8 through rivets 8a and 8b. The ends 4d and 5d of the standards 4 and 5 are each provided with upwardly extending pintles 4e and 5e which project through washer members 4f and 5f and form seats for the coil springs 9 and 10. Coil springs 9 and 10 are normally biased to a position from which the springs may contract under the load of the rider on the seat 11 of the figure. The coil springs are so biased that considerable cushion effect is secured, and under all normal conditions of loading, the coil springs are never fully compressed.

The sockets 6 and 7 and the frame of the figure 1 form pivot means for the operating links 12 and 14 of the control pedals 15 and 16. The pivot connections between the operating links 12 and 14 and the frame of the figure 1 and the tapered sockets 6 and 7 are represented at 17 and 18, passing through the end walls of the sockets 6 and 7 and displaced from the path of movement of the ends 4d and 5d of standards 4 and 5 into and out of sockets 6 and 7. The control pedals 15 and 16 are pivoted on members 19 and 20, passing through standards 4 and 4 immediately below shoulders 4c and 5c and immediately above shoulders 4b and 5b. The shoulders 4b and 5b are chamfered to enable control pedals 15 and 16 to move without obstruction about the shoulders 4b and 5b. To facilitate this movement, the control pedals 15 and 16 are shaped at 15a and 16a to provide a rounded surface between two limiting angularly disposed surfaces represented at 15b and 15c in Figs. 1 and 8, whereby control pedals 15 and 16 may be oriented through different angular positions without striking the chamfered surfaces 4b and 5b. The control pedals 15 and 16 are provided with extension links 15c and 16c at their extremities which connect with operating links 12 and 14 pivoted at 17 and 18 as heretofore explained. The control pedals 15 and 16 have feet engaging members 21 and 22 at their forward ends into which the feet of the operator may extend for manipulating the pedals and imparting angular movement to operating links 12 and 14 and correspondingly moving the figure forwardly or rearwardly with respect to the rockers 2 and 3. Reinforcement bars 23 and 24 are mounted in the rockers 2 and 3 on opposite sides of the pivotal connections 4a and 5a between the standards 4 and 5 and the rockers 2 and 3.

At opposite ends of the rockers, I provide pivotally mounted rods 25 and 26, the rods being carried centrally of transverse bars 25a and 26a, respectively, the transverse bars 25a and 26a being pivotally mounted between the semi-circular portions 2b and 2a at opposite ends of the runners, respectively. The rod member 25 and the pivotal mounting portion 25a thereof and also the rod mem-

ber 26 and the pivotal mounting 26a thereof are substantially in the shape of inverted T's with the vertically extending portions of the T's directed toward the hollow interior of the figure and the transverse portions of the T's serving to pivotally mount rods 25 and 26 in the rockable frame constituted by rockers 2 and 3. Rod member 25 extends angularly toward the central plane of the vertical standards 4 and 5 and projects through an elongated slot 27 formed in the head of the figure, the slot being of such length that the required angular displacement of the rod with respect to the figure is permitted. The upper end of rod 25 extends between brace bars 28 and 29 disposed transversely of the figure and within the hollow body of the figure and disposed in a plane which is substantially normal to the axis of the rod 25 when the figure is in normally balanced position. The end of the rod projects to a position approaching the center transverse plane of the figure and terminates in a head 25b under which there is engaged a frusto-conical coil spring 30, the lower end of which is secured to the bars 28 and 29 by twisted wire or thread shown at 28a and 29a. The normal position of coil spring 30 is depicted in Figs. 1 and 3. Fig. 5 illustrates the compressed condition of the coil spring during which potential energy is stored in the spring, while Fig. 6 indicates the expanded condition of the spring during which time kinetic energy is released by the spring simulating a bucking or prancing attitude of the figure.

The rearwardly located rod 26 is arranged in a manner similar but opposite to rod 25. The rod is inclined toward the central plane of the figure and projects between transverse bars 31 and 32 disposed in a plane substantially normal to the axis of rod 26 when the figure is in normal position. Rod 26 extends between bars 31 and 32 and through the convolutions of frusto-conical spring 33 which is confined on the end of rod 26 by head 26b. The end convolution of coil spring 33 is secured to transverse bars 31 and 32 by fastening cords or wires 31a and 32a. Fig. 1 shows the normal position for coil spring 33 with its convolutions sufficiently widely spaced to allow the coil springs to stretch or contract in accordance with the movement desired by the rider in seat 11. Upon compressing coil spring 33, potential energy is stored therein which is released as kinetic energy for bringing about a bucking or prancing attitude for the figure.

Figs. 9-14 show a progressive series of positions through which the figure may be moved under control of the operator. Fig. 9 represents a condition in which the figure is substantially erect and wherein there is no rocking or pedal movement, the figure and the mass of the rider being floatingly suspended on springs 9 and 10 and the front and rear movement being resisted by the normal bias exerted by front and rear coil springs 30 and 33.

However, the rider on seat 11 may effect a displacement of the pedals 15 and 16 as shown in Fig. 10, preparatory to the expansion of coil spring 30 and the compression of coil spring 33 as shown by the forward rocking movement depicted in Fig. 11.

Without changing the position of control pedals 15 and 16, the figure may be caused to rock on rockers 2 and 3 in accordance with the action represented in Fig. 12 wherein coil spring 30 is compressed while coil spring 33 is allowed to expand.

The figure may now be allowed to rock forward under control of the pedal movement as represented in Fig. 13 wherein spring 30 is allowed to expand while spring 33 is permitted to contract.

In Fig. 14 I have shown the condition in which the figure rocks rearwardly under control of pedal movement where coil spring 30 contracts while coil spring 33 expands. During all of these movements, the figure is floatingly mounted with respect to runners 2 and 3 by centrally arranged coil springs 9 and 10. Thus al-

ternate movements of the figure may be reproduced under control of the control pedals 15 and 16 and coil springs 30 and 33 rendered alternately effective to reproduce a bucking or prancing action as the potential energy stored in the springs is converted into kinetic energy in producing a sudden reactionary or kick-back force.

When the rider is mounted on the figure without any attempt at rocking, the weight is equally divided between the four springs 9 and 10 and 30 and 33, and springs 9 and 10 are compressed while springs 30 and 33 are stretched. As the rider rocks forward and the front bumpers 2b' and 3b' strike the surface of the floor represented at 34, the bumpers serve as safety devices to keep the figure from turning over and coil spring 30, for example, stretches beyond its normally biased position and coil spring 33 compresses to effect a kick-back action. When the rear bumper strikes the floor, a reverse of the action is secured. In Figs. 10, 13 and 14, the weight of the rider can be shifted to the control pedals 15 and 16 to give the effect of an upward lift. However, best results are obtained by pressing the control pedals 15 and 16 downwardly at the same time the bumpers 2b' and 3b' strike the surface of the floor. The release of potential energy under this condition is such as to impart an abrupt reaction or bucking effect to the figure. The extent of this reaction can be appreciated by comparing the position of the figure in Fig. 11 with the position of the figure in Fig. 13 and also the position of the figure shown in Fig. 12 as compared to the position of the figure shown in Fig. 14.

The forward and rearward rods 25 and 26 extend toward the centrally disposed plane which includes standards 4 and 5 and are disposed at acute angles thereto. The angularity of the rod members 25 and 26 varies as the figure is displaced on the frame constituted by the rockers 2 and 3. This variation, however, remains within the range of acute angles measured with respect to the central plane through the standards 4 and 5 and the figure.

While I have described my invention in certain preferred embodiments, I realize that changes may be made in details or construction, and I desire that it be understood that no limitations upon my invention are intended other than may be imposed by the scope of the appended claims.

What I claim as new and desire to secure by Letters Patent of the United States is as follows:

1. An amusement device comprising a rockable frame including a pair of rockers, a pair of standards extending vertically from said rockable frame and pivoted thereto, a hollow figure having a pair of sockets therein alignable with the upper ends of said standards, coil springs mounted in said sockets and serving to receive the upward extremities of said standards for floatingly suspending said figure with respect to said rockers, separate coil springs mounted within and supported on said figure on opposite sides of the aforesaid centrally arranged coil springs, rod members extending through said separate coil springs and individually connected with the ends thereof and pivotally connected to opposite ends of said rockable frame, whereby said figure may be displaced forwardly and backwardly for reproducing the combined reactionary effects from said separate coil springs.

2. A rockable figure comprising in combination a rockable frame, a pair of standards pivotally mounted at their ends in positions disposed centrally of said rockable frame and projecting vertically therefrom, a hollow figure, a pair of coil springs interposed between the hollow interior of said figure and the upper ends of said standards for floatatingly mounting said figure on said standards, forwardly and rearwardly arranged rod members pivoted to the front and rear portions of said rockable frame and separate coil springs interconnecting the

extremities of said last-mentioned rod members and the hollow interior of said figure for controlling in coaction with the aforesaid springs the forward and rearward yielding displacement of said figure.

3. An amusement device comprising a rockable frame structure, a figure, means supporting said figure with respect to said rockable frame structure comprising a pair of standards pivotally mounted on said rockable frame structure and extending substantially vertically therefrom, coil springs interposed between said figure and the ends of said standards, separate rod members pivotally mounted forwardly and rearwardly of said rockable frame and directed toward a central plane extending through the aforesaid standards substantially at acute angles thereto and coil springs interconnecting the ends of said last-mentioned rod members with said figure.

4. An amusement device comprising a hollow figure, a rockable frame, means supporting said hollow figure with respect to said rockable frame comprising a pair of substantially vertically extending standards pivotally mounted at their lower ends in said rockable frame, coil springs interposed between the upper ends of said standards and the hollow interior of said figure, a pair of inverted T-shaped members pivoted forwardly and rearwardly of said rockable frame, said inverted T-shaped members including rods directed into the hollow interior of said figure toward the aforesaid standards and coil springs interposed between said figure and the ends of said last-mentioned rods for suspending said figure with respect thereto.

5. An amusement device comprising a figure having a hollow interior, a pair of inverted tapered sockets mounted centrally within the hollow interior of said figure adjacent opposite sides thereof, a rockable frame, a pair of standards pivotally mounted in said frame and projecting vertically therefrom and into said tapered sockets, coil springs disposed between the ends of said standards and the bases of said sockets, whereby said figure is free to rock forwardly and rearwardly while floatatingly suspended on said coil springs limited by the taper of said sockets, control pedals pivotally mounted on said standards and connected with said figure for applying forces to said rockable frame and to said figure for rocking said frame for shifting said figure and means interposed between opposite ends of said rockable frame and opposite ends of said figure for yieldably resisting displacement of said figure.

6. An amusement device as set forth in claim 5 in which said means includes a pair of separate rod members pivotally mounted at opposite ends of said rockable frame and coil springs interposed between the ends of said separate rod members and said figure, whereby displacement of said figure in one direction expands one of said coil springs while compressing the other and wherein in movement of said figure in the opposite direction expands said last-mentioned coil spring while compressing the first-mentioned coil spring.

7. An amusement device as set forth in claim 5 in which said last-mentioned means comprise inverted T-shaped members having transverse portions journaled in said rockable frame structure and linear portions extending therefrom and directed to a substantially central position adjacent the aforesaid sockets, and coil springs interconnecting the linear portions of said T-shaped members and said figure for controlling the displacement of said figure toward and away from said rockable frame structure.

8. An amusement device as set forth in claim 5 in which said last-mentioned means comprise inverted T-shaped members having transverse portions journaled at opposite ends of said rockable frame and linear portions extending in a longitudinal plane between said tapered sockets, frusto-conical coil springs having their bases

secured to said figure and having their apices connected with the linear portions of said T-shaped members for effecting alternate expansion and compression operations as the figure reproduces a bucking action in similitude.

9. An amusement device as set forth in claim 1 including a pair of control pedals journaled on said standards and rockable with respect to said figure, and connections extending between said pedals and said figure and operative to rock said figure under control of said coil springs from forces exerted against said pedals.

10. An amusement device comprising a rockable support, a substantially hollow figure, means disposed substantially transversely of the axis of the hollow interior of said figure for floatatatingly supporting said figure over said rockable support, pedal members pivoted on said means, connections extending between said pedal members and said figure for applying displacement forces to said figure, rod members pivoted at opposite ends of said rockable support and extending upwardly at acute angles

5 to the plane of said centrally disposed means within said hollow figure, and coil springs interposed between each of the rod members and said figure and coacting to alter-

ately aid and oppose the forward and rearward displace-

10 ment of said figure with respect to the central transverse

plane through said means according to displacement

15 forces applied to said pedal members.
